FILING DEVICE

Richard J. Ambler, Montreal, Quebec, Canada

Application November 30, 1945, Serial No. 631,992

9 Claims. (Cl. 129—41)

1

My invention relates to filing means for holding sheets.

An important object of the invention is to provide a filing or holding device which will accommodate different thicknesses of stacks of sheets and will be flat when holding the stack in place.

A further object of the invention is to provide a filing device which will permit of the assembling of the sheets and which is adjustable to bring the sheets to the proper filing position.

A further object of the invention is to provide a filing or holding device which will properly retain the filed sheets against improper separation but permit of the quick removal of sheet or sheets when desired.

A further object of the invention is to provide a filing or holding device having a friction action and will thereby prevent undue downward movement of the stack of sheets upon the folder when the folder is suspended at the top.

A further object of the invention is to provide a filing or holding device which is adjustable within limits, while connecting the sheets, and is extensible to provide a loop of increased size, whereby the individual sheet or stack of sheets may be circulated or folded to an open position, and two groups of sheets arranged flat in end to end relation, rendering their entire surfaces visible.

A further object of the invention is to provide a flexible and adjustable filing device which is applied to a folder and will be securely attached thereto and properly hold the sheets to the folder, permit of their quick and easy circulation, inspection and removal.

A further object of the invention is to provide a file holder and filing or holding device or devices which may be completely assembled prior to use.

A further object of the invention is to provide a filing device having one side smooth for easy filing of the sheets and the other side somewhat roughened to aid in the friction holding principle.

Other objects and advantages of the invention will be apparent during the course of the following description.

In the accompanying drawings forming a part of this application, and in which like numerals are employed to designate like parts throughout the same,

Figure 1 is a perspective view of filing or holding devices embodying my invention, showing the same applied to a folder and stack of filed sheets, the folder being open,

Figure 2 is an end elevation of the same,

2

Figure 3 is an enlarged plan view of the filing devices in use, parts of the folder being broken away,

Figure 4 is a longitudinal section taken on line 4—4 of Figure 3,

Figure 5 is a horizontal section taken on line 5—5 of Figure 3,

Figure 6 is a similar view taken on line 6—6 of Figure 3,

Figure 7 is a side elevation of one filing or holding device removed and arranged flat,

Figure 8 is a side elevation of the folder and filing or holding devices of Figure 1, showing the same used in connection with a thin stack of sheets,

Figure 9 is a longitudinal section taken on line 9—9 of Figure 8,

Figure 10 is a plan view of the filing devices and holder, embodying a modification of the invention, wherein the filing devices are horizontal, the folder being open,

Figure 11 is a horizontal section taken on line 11—11 of Figure 10,

Figure 12 is a plan view of the filing or holding devices and folder, showing a further modification of the invention, wherein three horizontal filing or holding devices are used, the folder being open,

Figure 13 is a plan view of a modified form of folder,

Figure 14 is a similar view showing a filing or holding device and sheet or sheets in place, parts of the folder being broken away.

Figure 8^a is a fragmentary plan view of the holder shown in Figures 1 and 8.

The first form of the invention is shown in Figures 1 to 8 inclusive and Figure 8^a. The numeral 20 designates a folder which may be formed of stout paper or the like, foldable upon lines 21, 40 forming sides 22 and 23 and a back 24. The side 23 is provided at its top with reinforcing strips 25, formed of suitable material, such as paper, fabric or the like. These reinforcing strips are secured to the side 23 by glue, cement or the like.

45 In this embodiment of the invention, the folder is designed for receiving sheets 26, having two spaced holes 27 at their tops. The long slots 28 are formed through the side 23 and reinforcing strips 25, see more particularly Figure 8^a, and 50 short slots 29 are formed through these parts. The short slots are spaced downwardly from the long slots and are longitudinally centered with relation thereto.

Two filing or holding devices 30 are employed. 55 Each filing or holding device is integral and is formed from a flexible non-elastic sheet, such as

stout paper, fabric, leather, plastics or the like. The filing or holding device is preferably stamped from a flat sheet. The filing or holding device comprises a straight wide strip 31, having its free end rounded, as shown at 32. At its opposite end, the wide strip 31 has a transverse head 33 projecting laterally beyond the strip, forming extensions 34, having shoulders 35 and 35'. The strip 31 is provided with a group of longitudinally spaced transverse slots 36, and is provided between its free end and this group of slots with a preferably circular opening 37. Formed integral with the head 33 is a narrow straight strip or tail 38, and this narrow strip or tail has a locking head 39, formed integral therewith. This locking head 39 is wider than the narrow strip 38 and projects laterally beyond the same and is foldable upon longitudinal lines 40. When the locking head 39 is folded upon the lines 40, it may be inserted through the opening 37. The locking head 39, when flat, may be passed through any selected slot 36 and through the slot 29.

It is preferred that the filing or holding devices 30 be applied to the folder 20 before the folder is used for receiving the sheets 26 to be filed. In applying each filing or holding device 30 to the folder, each filing or holding device is first arranged upon the bottom or rear face of the side 23 and the rounded end 32 of the wide strip 31 is passed through the slot 28 and the locking head 39 is passed flat through the short slot 29. The wide strip 31 and narrow strip 38 are now pulled toward the front or inner face of the side 23 and the transverse locking head 34 becomes positioned upon the outer face of the reinforcing strip 25 and the shoulders 35 are arranged adjacent to the long slot 28 and limit further movement of the wide strip 31 toward the long slot, while the shoulders 35' are arranged adjacent to the short slot 29 and limit the longitudinal movement of the narrow strip 38 toward the slot 29. The wide strip 31 and the narrow strip 38 both extend upon the inner or front face of the side 23. The folder may now be resting open horizontally upon a table or desk and the wide strip 31 may be circulated or bent upwardly beyond the side 23 to be out of the way. The sheets 26 are now placed upon the upper face of the side 23 and the locking head 39 of each filing or holding device 30 is bent upon the lines 40 and passed through the openings 27 in the sheets. In this manner, a suitable number of sheets are threaded upon the narrow strip 38 to produce a stack of the desired thickness. After this has been done, the narrow strip 38 is pulled upwardly, while a slight downward pressure by the finger is applied to the stack of sheets adjacent to the openings in the sheets, and this will bring the several sheets in the proper filing position. The wide strip 31 is now folded over the stack of sheets and the locking head 39 is passed flat through a selected slot 36, which is immediately above the openings 27 in the sheets. The slot 36 selected will depend upon the thickness of the stack of sheets. The narrow strip 38 now extends upon the outer or upper face of the wide strip. The locking head 39 is again folded upon the longitudinal lines 40 and is passed downwardly through the opening 37 and is then pulled so that the strips 31 and 38 are distended and lie flat. The locking head 39 is flattened and is now positioned adjacent to the free end of the wide strip 31 and is spaced longitudinally from the opening 37, and this permits of the loop formed by the wide and narrow strips and which surrounds the

top of the sheets, being distended, when desired. The flat locking head 39 cannot pass through the opening 37 unless the locking head is again folded upon the lines 40, thus securely attaching the stack of sheets to the folder. The narrow strip 38 may be passed through a plurality of slots 36, and will become arranged above and below the alternate webs between the slots 36. This will increase the frictional engagement between the strip 38 and strip 31. Ordinarily, there is sufficient frictional engagement between the strips 31 and 38 when the strip 38 is passed through the opening 37 and one slot 36. As stated, when the strip 38 is passed through the opening 37 and pulled straight, the locking head 39 is spaced from the opening 37. The locking head 39 does not ordinarily function to prevent displacement of the filed sheets, within limits, but prevents them from separating. Due to the frictional engagement between the strip 38 and strip 31, the side 23 may be grasped at the top while the stack of sheets 26 is supported by the filing or holding devices, and the stack will be supported while the locking heads remain spaced from the openings. The face 40 of the strip 38 and strip 31 are preferably roughened to increase their frictional engagement, while the opposite face 41 is smooth. This may be effected by any suitable means or the filing or holding device may be made from rough and smooth layers, providing a laminated construction. While it is preferred to have these rough and smooth faces, the invention is not restricted to the same.

When it is desired to move any suitable number of the sheets 26 to an open position, the sheets are swung over the upper end of the side 23, and when some of the sheets remain upon the side 23, upper and lower stacks and sheets are provided, which may be horizontally supported in end to end relation. This permits of the inspection of the entire surface of the sheets. When the stack of sheets are swung to the upper horizontal open position, the narrow strip 38 slides in the slot 36 and opening 37, until the locking head 39 engages with the wall of the opening 37. This distends the loop formed by the strips 31 and 38, permitting of the free circulation or opening movement of the sheets.

In Figures 8 and 9, the form of the invention shown in Figure 1 is repeated, but the filing or holding devices 30 are used with a thin stack of sheets 26. Since the stack of sheets is thin, the narrow strip 38 is passed through the upper slot 36, which would be located next to the openings 27. Further, the narrow strip may be passed through a plurality of slots 36, and is arranged above and below certain of the webs between the slots 36. This increases the frictional engagement between the strips 31 and 38.

In Figures 10 and 11, a further modification of the invention is shown. The same folder 20 is used, but the long and short slots 28 and 29 are vertically arranged adjacent to the folding line 21. The sheets 26 corresponding to the sheets 26 have openings 27' near their vertical edges. The same filing or holding devices 30 are used and the wide strip 31 is passed through the long slot 28 and the narrow strip 38 through the short slot 29. The narrow strip 38 is threaded through the openings 27' and the filing and holding device is manipulated, as explained in connection with the first form of the invention. In this form of the invention, two of the filing or holding devices 30 are used, and are horizon-

tally arranged, for coaction with the sheets having the two openings 27'.

The device shown in Figure 12 is identical with that shown in Figures 10 and 11, except that three of the filing and holding devices 30 are used, three sets of slots 28 and 29 being provided in the folder, and the sheets 26' having three openings 27', adjacent to their vertical edges.

In Figures 13 and 14, I have shown a further modification of the invention, wherein a folder is provided for use with sheets having two or three openings at their vertical edges. This folder includes the sides 22 and 23, foldable upon the lines 21. The side 23 is provided with upper and lower long vertical slots 42 and an intermediate long vertical slot 43, all of which are arranged adjacent to the folding line 21. The slot 43 is of a size to receive the wide strip and prevent the head 33 passing through the same. The slots 42 are longer than the slots 43 and longer than the head 33. Arranged opposite the slots 42 are two short vertical spaced slots 44, for receiving the head 39 flat and the narrow strip 38. Arranged opposite the slot 43 is a short slot 45, for receiving the head 39 flat and the narrow strip 38. The slot 45 is at the longitudinal center of the slot 43, while slots 44 are spaced equal distances from the ends of the slot 42.

When the folder, Figures 13 and 14, is used in connection with the sheets having three openings at their vertical edges, the outer openings are nearer to the ends of the sheets. Three filing or holding devices 30 must now be used. The wide strip 31 of the filing or holding device is passed through each of the slots 42, and the strip 31 is then shifted toward the outer end of the slot 42, so that the shoulder 35 will project beyond the outer end of the slot 42, and prevent the strip 31 pulling out. The narrow strip 38 is passed through the short slot 44. The narrow strip 38 is now threaded through the end openings in the sheets, and the filing and holding device manipulated as heretofore described. The strip 31 of a third filing and holding device is passed through the slot 43 and the narrow strip 38 through the slot 45, and this filing or holding device applied to the sheets as explained.

When the folder, Figures 13 and 14, is used in connection with sheets having two openings at their vertical edges, these openings are farther from the ends of the sheets. The strip 31 of the filing and holding device is passed through each slot 42 and shifted inwardly so that the shoulder 35 projects beyond the inner end of the slot 42, Figure 14. The narrow strip 38 is passed through the inner slot 44. The narrow strips 38 of the two filing and holding devices are threaded through the openings in the sheets and these filing and holding devices manipulated, as before described.

I also contemplate forming the long slots 28 and short slots 29 horizontally at the top of the side 23, Figure 13. When this is done, two of the filing or holding devices may be applied to the top of the side 23 for coaction with sheets having two openings at their tops. The slots 42 and 44; and 43 and 45, permit of the use of two or three horizontal filing and holding devices, for coaction with the sheets having two or three openings at their vertical edges.

The reinforcing strips 25 are shown as applied to the first form of the invention, but may be applied to all forms. While it is preferred to use these reinforcing strips, yet they may be

omitted if the folder is formed of sufficiently stout material.

It is to be understood that the forms of my invention herein shown and described are to be taken as preferred examples of the same and that various changes in the shape, size and arrangement of parts may be resorted to without departing from the spirit of my invention or the scope of the subjoined claims.

Having thus described my invention, what I claim is:

1. In filing apparatus an elongated wide flexible strip provided near one end with a transverse head which projects laterally beyond the longitudinal edges of the wide strip for forming stop shoulders, the wide strip having a longitudinal group of spaced transverse slots and an opening arranged between the group of slots and the free end of the wide strip, the opening having a shorter transverse dimension than the slots, and a second elongated narrow flexible strip secured to the end of the wide strip adjacent to the transverse head, the narrow strip being provided near its free end with a locking head extending laterally beyond the same, the locking head having a greater transverse dimension than said opening so that it must be folded to be passed through the opening, the locking head being adapted to be passed flat through the slots.

2. A filing apparatus for holding sheets, comprising a side provided with spaced slots, a flexible holding device comprising connected first and second flexible strips, the first strip having a transverse head near one end which projects laterally beyond the first strip to form stop shoulders and a group of spaced transverse slots and an opening arranged between the group of slots and its free end, said opening having a transverse dimension shorter than the lengths of the slots, the second strip having a laterally projecting locking head near its free end, said locking head having a width greater than the transverse dimension of said opening, the locking head of the second strip being foldable to reduce its width and adapted to be passed flat through a selected slot of the first strip and to be passed folded through the opening of the first strip, the first strip being inserted through one slot in the side and the second strip through the other slot in the side, the stop shoulders of the transverse head carried by the first strip projecting beyond the ends of the slots in the side, the second strip being passed through a selected slot in the first strip and through the opening in the first strip, the first and second strips being of substantially the same length when holding the sheets and the locking head of the second strip being spaced from the opening in the first strip so that the loop formed by the first and second strips may be distended.

3. A filing apparatus for holding sheets, comprising a side provided with spaced slots, a flexible holding device comprising connected first and second flexible strips, the first strip having a laterally projecting stop shoulder and a group of spaced transverse slots and an opening arranged between the group of slots and its free end, said opening having a transverse dimension smaller than the length of the transverse slots, the second strip having a laterally projecting locking head, the locking head having a width greater than the transverse dimension of said opening, the locking head of the second strip being foldable to reduce its width and adapted to be passed flat through a selected slot of the

first strip and to be passed folded through the opening of the first strip, the first strip being inserted through one slot in the side and the second strip through the other slot in the side, the stop shoulder of the first strip projecting beyond the ends of the slots in the side, said second strip being passed through a selected slot in the first strip and the opening in the first strip, the locking head of the second strip being spaced from the opening in the first strip when the first and second strips are holding the sheets so that the loop formed by the first and second strips may be distended.

4. A filing apparatus, comprising a side provided with spaced slots, a flexible holding device comprising first and second flexible strips arranged in end to end relation, the first strip having a laterally projecting stop shoulder near one end and a group of spaced transverse slots and an opening arranged between the group of slots and its free end, said opening having a smaller transverse dimension than the length of the slots, the second strip having a laterally projecting locking head near its free end, the locking head having a width greater than the transverse dimension of said opening, the locking head of the second strip being foldable to reduce its width and adapted to be passed flat through one slot of the side and a selected slot of the first strip and to be passed folded through the opening of the first strip, the first strip being inserted through one slot of the side and the second strip through the other slot in the side, the stop shoulder of the first strip projecting laterally between the end of the slot receiving the first strip.

5. A filing apparatus, comprising a folder having sides, one side having pairs of slots near its edge, one slot in each pair being long and the other short, flexible holding devices for coaction with the folder, each holding device comprising a wide strip and a narrow strip which are secured together, the wide strip having a laterally projecting stop shoulder and a longitudinal set of spaced slots and an opening, said opening having a transverse dimension less than the length of the slots the narrow strip having a laterally projecting locking head, the locking head having a width greater than the transverse dimension of said opening, the wide strips of the holding devices being passed through the long slots and the narrow strips of the holding devices through the short slots, the stop shoulder projecting beyond the ends of the long slots and the short slots of the side, the arrangement being such that each flexible holding device is held against longitudinal movement in either direction with respect to the side having the slots when the flexible holding device has its ends pulled longitudinally from the inner face of such side.

6. A filing apparatus, comprising a folder having sides, reinforcing strips secured to one side near its edge, such side and reinforcing strips having pairs of slots formed therein, one slot in each pair being long and the other slot short, flexible holding devices for coaction with the folder, each holding device comprising connected wide and narrow strips, the wide strip having a laterally projecting stop shoulder and a group of spaced slots and an opening, the opening having a transverse dimension less than the length of the slots, the narrow strip having a laterally projecting locking head, the locking head having a width greater than the transverse dimension of said opening, the wide strips of the holding devices being passed through the long slots and

7. the narrow strips through the short slots the stop shoulder projecting beyond the ends of the long and short slots of the side, the arrangement being such that each flexible holding device is held against movement in opposite directions with respect to the side having the slots when the ends of the flexible holding device are pulled longitudinally from the inner face of such side.

7. A filing apparatus, comprising a folder having sides, one side being provided near its edge with pairs of horizontal spaced slots, and holding devices for coaction with the folder, each holding device comprising connected first and second strips, the first strip having a laterally extending stop shoulder and a group of spaced slots and an opening, said opening having a transverse dimension less than the length of the slots, the second strip having a laterally projecting locking head, the locking head having a width greater than the transverse dimension of said opening, the first strip being passed through one slot in each pair and the second strip through the other slot in such pair the stop shoulder extending beyond the ends of the slots in the side, the arrangement being such that the shoulder holds the holding device against movement in opposite directions with relation to the side provided with the slots when the ends of the holding device are pulled longitudinally from the inner face of the side.

8. A filing apparatus, comprising a folder having sides, one side being provided near one edge with pairs of vertical spaced slots, and holding devices for coaction with the folder, each holding device comprising flexible connected first and second strips, the first strip having a laterally projecting stop shoulder and a group of spaced slots and an opening, the opening having a transverse dimension less than the length of the slots, the second strip having a locking head, the locking head having a width greater than the transverse dimension of said opening, the first strips being passed through the slots in the pairs and the second strip through the other slots in the pairs, the stop shoulder extending beyond the ends of the slots in the pairs, the arrangement being such that the stop shoulder holds the holding device against movement in opposite directions with respect to the side having the slots when the ends of the holding device are pulled longitudinally from the inner face of such side.

9. A filing apparatus, comprising a folder having sides, one side having longitudinally spaced long slots and a pair of spaced short slots arranged near each long slot, the long slot extending beyond the pair of short slots, and flexible holding devices for coaction with the folder, each holding device comprising connected wide and narrow strips, the wide strip having a stop shoulder and a plurality of longitudinally spaced openings, the narrow strip having a locking head, the wide strip being inserted through the long slots which are longer than the width of the wide strips, the narrow strips being inserted through selected slots in the short pairs, the stop shoulder extending outwardly beyond the ends of the long slot and short slot in the side, the arrangement being such that the shoulder holds the flexible holding device against movement in opposite directions with respect to the side having the slots when the ends of the holding device are pulled longitudinally from the inner face of such side.
